UNITED STATES PATENT OFFICE.

ALBERT L. JOHNSON, OF ST. LOUIS, MISSOURI, ASSIGNOR, BY DIRECT AND MEGNE ASSIGNMENTS, TO CORRUGATED BAR COMPANY, OF ST. LOUIS, MISSOURI, A CORPORATION OF MISSOURI.

CORRUGATED BAR.

982,682.

Specification of Letters Patent. Patented Jan. 24, 1911.

Application filed February 19, 1908. Serial No. 124,362.

To all whom it may concern:

Be it known that I, ALBERT L. JOHNSON, a citizen of the United States, and a resident of the city of St. Louis and State of Missouri, have invented a new and useful Improvement in Corrugated Bars, of which the following is a specification.

My invention relates to corrugated bars and especially to corrugated bars for metal concrete construction and has for its principal objects to provide a bar having spaced transverse projections on its faces arranged in rows longitudinally of the bar, the rows being arranged in complementary sets and the relation of the rows of each set to each other being fixed; to utilize the projections to contribute to the tensile strength of the bar; to provide a corrugated bar having longitudinal rows of projections and spaces arranged in sets, the projections and spaces being so proportioned that at any cross-section of the bar the area of one or more projections will compensate for the reduction in area by the spaces; to provide a corrugated bar of such construction that any transverse section will pass through at least as many projections as spaces between projections; to provide a corrugated bar of such construction that any transverse section will pass through projections upon at least one half of the faces of the bar; and to attain other objects hereinafter more fully appearing.

My invention consists in a corrugated bar having longitudinal rows of alternate transverse projections and spaces, a plurality of which rows bear a fixed relation to one another.

In the accompanying drawings forming a part of this specification and wherein like symbols refer to like parts wherever they occur, Figure 1 is a perspective view of my improved bar; Fig. 2 is a section on the line 2--2 of Fig. 1; Fig. 3 is a side view of the bar resting on edge; Fig. 4 is a section on the line 4--4 of Fig. 3; Fig. 5 is a development of the bar; Fig. 6 is a development of the bar in the form in which it is preferred to make it; Fig. 7 is a cross-section of a circular bar embodying my invention; Fig. 8 is a section on the line 8--8 of Fig. 7; Fig. 9 is a view of one face of a modified form of bar; Fig. 10 is a cross section of a bar of triangular cross section having faces conforming to the modification shown in Fig.

9: Fig. 11 is a perspective view of a circular bar embodying my invention; Fig. 12 is a side view of the round bar shown in Fig. 11; Fig. 13 is a side view of the round bar turned a quarter turn with respect to the position of the bar in Fig. 12; and Fig. 14 is a cross section of an elliptical bar embodying my invention, the arrangement being similar to the round bar.

In metal concrete construction it is desirable to use corrugated bars for many reasons. The hitherto known forms of such bars have projections that are narrow in comparison with the spaces between them. Consequently, there are transverse sections which do not pass through a single projection. In such a bar the projections do not contribute to the tensile strength, for a bar is only as strong as its weakest section. The bar is necessarily heavy for the minimum section must contain enough metal to give the required strength, and to this is added the weight of the projections for example, see Patent No. 633,285, issued to me September 19, 1899.

In my improved bar the projections are similar to those in the bars shown in my prior patent but are so arranged and proportioned as to contribute to the tensile strength. This is accomplished by arranging the projections and spaces so that any transverse section will pass through at least as many projections as spaces. In a bar of given strength it is necessary for a section through two projections and two spaces to have only the area of the minimum section of the old form of bar. Thus the bar will be of substantially the weight of a plain bar having a section equal to the minimum section of the old form of bar. An amount of metal equal to the weight of the projections on the old form of bar is therefore saved.

The bar is preferably quadrangular in cross-section, each of the faces having alternate projections 1 and spaces 2. The projections preferably have flat faces 3 and beveled edges 4.

The bars are preferably rolled by rollers having angular grooves, the upper roll forming two faces of the bar, and the lower roll forming the other two faces. The relative position of the projections and spaces on one of the two faces made by the same roll with respect to the projections and spaces on the other face is fixed. But on account of

the possible relative movement of the two rolls, the relative position of the projections and spaces upon the faces made by one roll with respect to the projections and spaces upon the faces made by the other roll is likely to be variable.

In a bar having an exactly constant cross-section the projections upon one of the two faces made by the same roll are in line with the spaces on the other of said faces; the beveled edges of the projections are in line with each other; and the faces of the projections equal in width the spaces between the projections. Therefore considering a triangular section formed by a plane in the line of contact of the rolls as indicated by the dotted line in Fig. 4, all transverse sections are equal. This is true of both the triangular sections making the complete bar. Hence, the cross-section of the bar is constant however much the two triangular sections may be relatively displaced with respect to each other on account of the relative movement of the rolls mentioned above. This may be clearly seen by an inspection of Fig. 5 which is a development of the bar, or a view of the bar such as would be had if it were opened out so that its four faces were in the same plane. It shows all four faces, the pair of faces made by one roll being displaced with respect to the pair of faces made by the other roll, approximately half the width of the space in this figure. The diagonally opposite corners of the bar formed at the meeting point of the two rolls are slightly truncated. The spaces terminate in a wall substantially parallel with the line of contact of the rolls and substantially perpendicular to the truncated corner. The preferred form of bar is illustrated by Fig. 6 which is a development thereof. It differs from the bar just described only in the relative location of the beveled edges of the projections upon the two faces made by the same roll. The pairs of beveled edges upon these faces, instead of being in line with each other, are displaced by an amount substantially equal to their width so that each is opposite the body of the projection upon the adjacent face. This form is substantially of constant cross-section and is a more practicable form to roll. If rolls were designed to roll the form of exactly constant cross-section they would soon wear so as to produce substantially this preferred form. The preferred form has also the advantage of increased strength in the line of angular fracture across the diagonals of the spaces between projections. A fracture cannot extend from a space on one face to a space on an adjacent face without passing through a portion of at least one projection. This increased strength is secured with an increase in weight that is practically negligible.

A bar of circular cross-section is illustrated in Figs. 6 and 8. This bar differs from the quadrangular bar just described only in having cylindrical faces instead of flat faces. In practice such a bar is rolled in rollers having semi-circular grooves. Thus one pair of rows of alternate projections and spaces may be made by each roll and the relation of the rows made by the same roll is fixed. Obviously, more than a pair of rows of projections and spaces could be impressed by the small roll and the metal so distributed that at any section the area of one or more projections should be at least as great as the reduction in the area due to spaces. A bar having any number of faces may be employed.

A modified form of face applicable to a bar having any number of faces is shown in Fig. 9. The face is provided with two rows of alternate projections 1 and spaces 2. The projections of one row are staggered with respect to the projections of the other row in the same manner that the projections of the rows upon different faces are arranged in the forms described above. A section of a triangular bar of substantially constant cross-section embodying this modification is illustrated in Fig. 10.

In Fig. 8 the concrete 5, in which the corrugated bars are embedded in use is shown. The concrete has been omitted from the other figures as its presence would serve to obscure the features of the bar.

Obviously, my device is capable of considerable modification within the scope of my invention and therefore I do not wish to be limited to the specific construction shown and described. For instance, the bar may be elliptical in cross-section, the circular bar illustrated in Figs. 7 and 8 being simply a particular case of the elliptical bar.

What I claim as my invention and desire to secure by Letters Patent is:

1. A corrugated bar having a plurality of faces and spaced transverse projections on each face, said projections being arranged in rows longitudinally of the bar, the rows of projections arranged in pairs, each pair having the projections in one row so arranged with respect to the projections in the other row that the sectional area of the bar at any point is substantially equal to the sectional area at any other point.

2. A corrugated bar having a plurality of faces and spaced transverse projections on each face, said projections being arranged in rows longitudinally of the bar and the projections of each row being separated by spaces, the rows of projections being arranged in pairs, of each pair of which the projections of one row are in line with the spaces of the other row, and each projection being at least as wide as the space in alignment therewith.

3. A corrugated bar having a plurality of faces and alternate transverse projections and spaces upon each face arranged in longitudinal rows, the projections of each row being in line with the spaces, respectively, of one of the adjacent rows, and the projections being so proportioned with respect to the spaces in alignment therewith that any transverse section through the bar will pass through at least as many projections as spaces.
4. A corrugated bar having a plurality of pairs of faces and transverse projections on each face separated by spaces, the projections on each face of each pair of faces being in line with the spaces upon the other face of the same pair of faces.
5. A corrugated bar having a plurality of faces, and alternate transverse projections and spaces arranged in rows on said faces, a plurality of said rows having a fixed relation to one another, the projections and spaces of said rows being staggered with respect to one another, and each projection being at least as wide as the space in alignment therewith.
6. A corrugated bar having a plurality of pairs of faces and alternate projections and spaces upon each face, the projections upon one face of each pair of faces being staggered with respect to the projections upon the other face of said pair of faces, whereby any transverse section will pass through at least as many projections as spaces.
7. A corrugated bar having a plurality of pairs of faces and transverse projections on each face separated by spaces, the projections on each face of each pair of faces being in line with the spaces, respectively, upon the other face of said pair of faces, and each projection being at least as wide as the space in alignment therewith.
8. A corrugated bar having a plurality of pairs of faces and bevel-edged projections upon each face separated by spaces, the faces of said projections being at least as wide as the spaces, and the projections
- upon one face of each pair of faces being in line with the spaces upon the other face of said pair of faces.
9. A corrugated bar of quadrangular cross-section having alternate projections and spaces on all its faces, the projections on each face being staggered with respect to the projections on one of the adjacent faces and said spaces being of substantially uniform depth from projection to projection.
10. A corrugated bar of quadrangular cross-section having alternate projections and spaces on all its faces, the projections on each face being in line with the spaces, respectively, on one of the adjacent faces and being so proportioned with respect to the spaces in alignment therewith that any transverse section through the bar will pass through at least two projections.
11. A corrugated bar of quadrangular cross-section having alternate projections and spaces on all its faces, the projections on each face being in line with the spaces, respectively, on one of the adjacent faces and each projection being at least as wide as the space in alignment therewith.
12. A corrugated bar of quadrangular cross-section having bevel-edged projections on all its faces separated by spaces, the faces of said projections being at least as wide as the spaces, and the projections upon each face being in line with the spaces, respectively, on one of the adjacent faces.
13. A corrugated bar of quadrangular cross-section having alternate transverse projections and spaces, the projections on one face being centrally aligned with the spaces, respectively, on one of the adjacent faces, the projections being slightly wider than the spaces in central alignment therewith.

In testimony whereof I have signed my name to this specification in the presence of two subscribing witnesses,

ALBERT L. JOHNSON,

In the presence of -

FRED F. REINER,

R. LINCOLN MURPHY.
